UNITED STATES PATENT OFFICE.

WILLIAM R. BASSICK, OF BRIDGEPORT, CONNECTICUT, ASSIGNOR TO THE BASSICK COMPANY, OF BRIDGEPORT, CONNECTICUT, A CORPORATION OF CONNECTICUT.

AUTOMOBILE HOOD CLAMP.

Application filed January 28, 1922. Serial No. 532,435.

To all whom it may concern:

Be it known that I, WILLIAM R. BASSICK, a citizen of the United States, and resident of Bridgeport, in the county of Fairfield 5 and State of Connecticut, have invented certain new and useful Improvements in Automobile Hood Clamps, of which the following is a specification.

The invention relates to improvements in 10 automobile hood clamps. It has for its object the provision of improved clamping devices whereby the engine hood may be secured in an effective manner to the frame of an automobile, the clamping devices being designed to prevent rattling, to be self 15 adjusting, to be efficient and simple in operation, and inexpensive to manufacture. My preferred clamping devices comprise a hold-down clamp and a side engaging clamp 20 which are connected to operate together, spring means for forcing the clamps downwardly and cam means, or means acting at an inclination, whereby the spring action not only serves to press the hold-down clamp 25 downwardly, but also tends to force the side engaging clamp laterally, towards the hood. Other objects of the invention consist in the various combinations of parts and details of construction embodied in the 30 device, all as will be more fully set forth in the following specification, and particularly pointed out in the appended claims.

In order that the invention may be more clearly understood attention is hereby directed to the accompanying drawings forming part of this application and illustrating certain embodiments of the invention. In the drawings—

Fig. 1 represents a vertical section taken 40 on line 1, 1, of Fig. 2;

Fig. 2 is a front elevation of a clamping device embodying one form of the invention;

Fig. 3 is a top plan view of the device, 45 the hood being shown in section;

Fig. 4 is a horizontal section taken on line 4—4, of Fig. 1;

Fig. 5 is a vertical section taken on line 5—5 of Fig. 6;

Fig. 6 is a front elevation of a modified 50 form of the device;

Fig. 7 is a top plan view of the same, the hood being shown in section; and

Fig. 8 is a horizontal section taken on 55 line 8—8 of Fig. 5.

Referring first to Figs. 1 to 4 of the drawings the engine hood, indicated at 1, is to be clamped to the frame of the automobile, a portion of which is indicated at 2. The hood is to be clamped against an up-standing portion of the frame which is illustrated as a flange 3 on the frame portion 2.

A hold-down clamp, as illustrated, comprises a hook 4, which extends laterally and downwardly from a barrel 5. The latter 65 is illustrated as having a boss 6 formed on one side thereof, adjacent its lower end, which boss forms a seat against which a pad 7 of rubber or other desired material is secured, as by means of the screw 8. 70

A base bracket 9 is secured to the automobile frame member 2, as by means of securing devices such as screws 10, or it may, of course, be integral with a frame member. This base bracket is formed, in the 75 embodiment of the invention illustrated, to provide a central portion 11 which extends toward hood 1 at a rising inclination, this inclined portion 11 of the bracket having a slot 12, extending therethrough, this slot 80 extending in the axial direction of the bracket, that is, towards hood 1. It will be understood that the invention is not limited to the use of the slot 12 in the inclined portion of the base bracket, but that 85 other suitable inclined guiding means may be used.

In the form of device illustrated a rod 13 extends longitudinally through barrel 5. This rod is illustrated as provided at its 90 upper end with a portion 14 of enlarged diameter which slidably engages in a suitable opening at the upper end of barrel 5. Preferably the barrel is provided with integral handle portions 15, 15, extending 95 from opposite sides of the upper end of the barrel, this construction serving to close the upper end of the barrel except for the opening in which the portion 14 of rod 13 slidably engages. Barrel 5 is closed at its lower end except for an opening through which rod 13 slidably engages.

A spiral spring 16 is shown as coiled about rod 13 within barrel 5, this spring bearing at its upper end against the peripheral shoulder formed at the lower end of the enlargement 14 while the lower end of the spring bears against the lower end portion 17 of the barrel. Accordingly, the spring being pressed between enlargement 100 105 110

14 and the end portion 17 of the barrel, it constantly tends to push rod 13 upwardly and to press barrel 5 downwardly.

The hook, or hold-down clamp 4, is adapted to coact with some form of strap or bracket secured to hood 1. Preferably this takes the form of a bracket 18 formed of pressed metal, having a downwardly and inwardly slanting front wall 19 over which the hook 4 may be engaged. Preferably front wall 19 of this bracket is provided with an inwardly extending shoulder 20 against which the nose of hook 4 may press. This shoulder is preferably formed by slitting the metal of the front wall 19 of the bracket, as indicated at 21, and pressing the tongue thus formed upwardly and inwardly, to constitute the abutment 20, 20, as shown. The provision of this abutment 20 tends to prevent the wearing through of the front wall 19 of the bracket, or wear of hook 4, under the repeated application of hook 4 to the bracket.

Rod 13 extends through slot 12 in the inclined bracket member 11, rod 13 having an enlargement 22 at its lower end, which cannot pull up through slot 12. Enlargement 22 is preferably provided with a smoothly curved upper surface 23 which is adapted to slidingly engage against the under surface of the inclined portion 11 of bracket 9 adjacent to slot 12. The curved upper surface of enlargement 22 may also serve as a fulcrum about which the device will rock when surface 23 is pressed against the under surface of the inclined member 11. A pin 24, or the like, may be extended through rod 13 to serve as a stop or seat against which the lower end portion 17 of barrel 5 may engage when hook 4 is not in engagement with its bracket 19.

In operation, it is only necessary to raise handles 15 relative to rod 13, sufficiently to enable hook 4 to slip over the upper edge of bracket 19. This being accomplished, the upward inclination of the portion 11 of bracket 9 will cause the lower end of the clamping device to move towards hood 1 to press clamping member 7 firmly against hood 1. This is, of course, because of the fact that the spring 16 is pulling upwardly on rod 13 and the lower end of the latter has a slideable bearing portion engaging against the under side of an inclined surface; accordingly the upwardly directed force tends to cause the bearing surface 23 of rod 13 to slide upwardly and laterally as permitted by the inclination of member 11. Accordingly the lower clamping member 7 of the device will move laterally against hood 1 and be pressed firmly thereagainst, the whole clamping device in effect swinging about hook 4 as a fulcrum, to place clamping member 7 in its operative position.

With such an arrangement it is obvious

that the hood will at all times be held down firmly against member 2 and be pressed laterally against flange 3 so as to prevent rattling thereof. It will also be obvious that the device is self adjusting and that the 70 inclination of member 11 acts in effect to cam member 7 laterally against the hood whenever rod 13 is pulled upwardly and that this action will cause a firm bearing of member 7 against the hood at all times regardless of any slight wear in member 7.

The device may take various forms within the spirit of the invention. In Figs. 5 to 8 of the drawings I have illustrated a similar device in which the lower end of the rod 80 13 is provided with an eye 25 which engages over an inclined rail 26. Rail 26 may be formed as an inclined portion of a bent rod, the two ends of which are provided with screw threads and inserted through openings in frame member 2, to which they are secured by means of nuts 27, as indicated.

Also in this form of device the bracket 18¹ secured to the hood 1 is illustrated as provided with a downwardly extending portion 90 18^a, which rests against the hood below the outwardly flaring portion 18^b of the bracket, over which the hook 4 engages. The bumper, or clamping member 7^a, is shown as secured to portion 18^a of bracket 18¹, as by 95 means of the counter-sunk screw 27', clamping member 7^a being of rubber or other suitable material. With this form of device the effect is, of course, the same, the side of barrel 5 engaging against clamping member 7^a when hook 4 engages in position and spring 16 pulls upwardly on rod 13, causing eye 25 to tend to slide towards the hood along rail 26. In the claims the term "side 100 engaging surface" will be understood as a generic expression to indicate surface on the barrel which bears laterally against the hood, this term indicating either the bumper 7 on the barrel in the construction shown in Fig. 1, or the surface of the barrel which engages the bumper 7^a on the hood in the construction shown in Fig. 5.

In this form of construction the barrel 5 is illustrated as being closed by a covering member 28 which may be suitably secured thereto, and which has the hook 4 and the handle members 15 formed integral therewith. With this construction the rod 13 is provided at its upper end, within the barrel, with a shoulder 14¹ against which the upper 115 end of spring 16 may press.

It should be understood that the invention is not limited strictly to the details of construction described but is as broad as is indicated by the accompanying claims.

What I claim is:—

1. In an automobile hood clamp, the combination of a member, a hold down clamp and a side engaging surface carried thereby, means for resiliently pressing the same 120

- downwardly, and means, including an inclined member, and means carried by said first named member and slidably engaging said inclined member, for pressing said side 5 engaging surface into contact with the hood which is to be clamped, as said resiliently pressing means operates, said inclined member being of such length as to cause such operation regardless of wear between said side 10 engaging surface and hood.
2. In an automobile hood clamp, the combination of a hold down clamp and a side engaging surface, means, including a spring, for pressing said clamp, when adjusted in 15 position, down against a portion of a hood, and means, including an immovably fixed inclined member, for pressing said side engaging surface into contact with the hood, during the operation of said spring, said inclined member being inclined in the same 20 direction throughout its length.
3. In an automobile hood clamp, the combination of a hold down clamp and a side engaging surface, a member by which the same are both fixedly carried, and coacting means, 25 including a spring, for presssing said clamp, when adjusted in position, down against a portion of a hood, and at the same time pressing said side engaging surface towards 30 the hood, and into engagement therewith, regardless of wear between said surface and hood.
4. In an automobile hood clamp, the combination of a member carrying a hold down 35 clamp at its upper end and a side engaging surface at a lower point, and means for forcing said clamp down upon a coacting portion of a hood, when adjusted thereon, and at the same time swinging said member to- 40 wards the hood, about the engaging portion of said clamp as a fulcrum to press said side engaging surface against the hood, regardless of wear between said side engaging surface and hood.
5. In an automobile hood clamp, the combination of a member carrying a hold down 45 clamp at its upper end and a side engaging surface at a lower point, a member longitudinally slidable relatively to said first member, a spring coacting with both mem- 50 bers to press the first named member down and the second named member up, relatively to each other, and an inlined guiding abutment engaged by said second member when 55 said clamp presses down on the hood,
- adapted to cause the upward pressure of said second member to press said side engaging surface into contact with the hood, said abutment being inclined upwardly towards said hood throughout its length. 60
6. In an automobile hood clamp, the combination of a member carrying a hold down clamp at its upper end and a side engaging surface at a lower point, a rod longitudinally slidable through bearings in said member, 65 a spring coacting with said member and rod to press the former down, and the latter up, relatively to each other, and a fixed guiding abutment inclined to the axis of said rod, said rod having a lower end portion 70 adapted to slidably coact with said abutment, said abutment being inclined in the same direction throughout its length.
7. In an automobile hood clamp, the combination of a member carrying a hold down 75 hook at its upper end and a side engaging surface at its lower end, a rod longitudinally slidable through bearings in said member, a spring adapted to press said member down and said rod up, relatively to each other, a 80 frame member, a hood member to be clamped thereto, and a bracket on the hood member over which said hook engages, said frame member having a portion inclined towards said hood member, said rod having a lower 85 end portion slidably coacting with said inclined portion, said inclined portion being inclined upwardly towards said hood member throughout its length.
8. In an automobile hood clamp, the combination of a member carrying a hold down 90 hook at its upper end and a side engaging surface at its lower end, a rod longitudinally slidable through bearings in said member, a spring adapted to press said member down 95 and said rod up, relatively to each other, a frame member, a hood member to be clamped thereto, a bracket on the hood member over which said hook engages, and means for swinging the lower end of said member 100 towards the hood member when said hook engages over said bracket, said bracket having a lower extension with a buffer secured thereon against which said side engaging surface will press. 105

Signed at New York, in the county of New York, and State of New York, this 26th day of January A. D. 1922.

WILLIAM R. BASSICK.
